Primary Examiner — George D. Kirschbaum*Assistant Examiner* — Patricia K. Beard(74) *Attorney, Agent, or Firm* — Harris Beach Murtha Cullina PLLC(57) **CLAIM**

The ornamental design for a puzzle ball as shown and described.

DESCRIPTION

FIG. 1 is a front perspective of a puzzle ball in accordance with the new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines show in FIGS. 1-7 are for the purpose of illustration portions of the puzzle ball that form no part of the claimed design.

1 Claim, 7 Drawing Sheets(56)
